CONVERTIBLE TABLE

Norval P. Schreiner, Springfield, Mo.

Application April 27, 1944, Serial No. 533,045

6 Claims. (Cl. 311—3)

1

This invention relates to convertible tables, and particularly to a knee-hole desk adapted to be converted into a dining table.

In many small homes, and especially in apartments, floor space is limited to the extent that many desirable pieces of furniture are necessarily excluded. The provision of a dining table, indispensable as it is, introduces under these circumstances, a major problem in outfitting the home. The conventional dining table occupies a great deal of floor space and except for limited periods at meal times it serves no useful purpose.

It is the principal object of the present invention to provide a piece of furniture which normally comprises a small, but highly desirable article of great utility, such as a knee-hole desk, and which can easily and quickly be converted into a dining table of liberal proportions.

One of the objects of my invention is to provide a convertible piece of this character which is capable of conversion into a table of any of several degrees of expansion to accommodate the particular need at hand, including a size suitable for use as a breakfast table or card table.

A further object is to provide a device of this character in which the portions serving as supports or legs may be optionally disposed in various positions with respect to the table top so that an arrangement of these parts may be made which will provide maximum seating space and comfort to the particular number of persons to be seated.

An additional object of the present invention is to provide a convertible dining table which requires little adjustment in conversion from one stage to another and which has no hinged props, arms or swinging supports which may accidentally become displaced.

Another object of my invention is to provide a device of this character in which liberal drawer space is provided for storing silver-ware, table linens, etc., as well as other items of more general daily use such as writing materials or other items normally occupying a desk.

Other objects and advantages will be apparent from the following description, the accompanying drawings and the appended claims.

In the accomplishment of these objects I have provided four pedestals which serve as legs or supporting columns for the table top and which may be equipped with drawers, the pedestals or drawer cabinets being arranged in two pairs, each pair comprising a front and a rear pedestal which are interconnected by slide means which permit them to be positioned in juxtaposed or spaced relation. The main table top is divided into front and rear sections, each of which is provided with longitudinal slide guide means. Each of the front and rear pedestals carry transverse slide guide means. Combinations slides

2

comprising longitudinal and transverse slides in crossed or right angled relation are adapted to slide either longitudinally of the table top or transversely of the pedestals, whereby the individual pedestals may be moved forwardly or rearwardly with respect to each other or in respect to either front or rear table top sections and the pairs of pedestals may be moved longitudinally of the table top. By this arrangement of pedestals, slides and divided main table top the pedestals may be arranged in various combinations and the table top sections may be spaced transversely to accommodate additional leaves.

A folding top section is hinged to the rear main top section and adapted to be either folded forwardly in superposed relation to the main top sections when used as a desk or extended rearwardly in coplanar relation with the main top sections when used as a table.

20: In further detail and with reference to the accompanying drawings:

Fig. 1 is a perspective view, partly in fragmentary section, showing the front and rear pedestals partially separated transversely and with the table top partially extended and the folding top section extended coplanar with the main top sections.

Fig. 2 is a top view, partly in fragmentary section, showing the pedestals fully separated transversely and with the table top fully extended and two auxiliary leaves inserted.

Fig. 3 is an end view corresponding with Fig. 2 with respect to positioning of the parts.

Fig. 4 is a fragmentary end view showing the device completely contracted and with the folding top section disposed on top of the main table top sections.

Fig. 5 is a front view showing the device as a knee-hole desk.

Fig. 6 is a front view showing the device extended and with the pairs of pedestals moved together longitudinally.

Figs. 7 to 11, inclusively, are diagrammatic top views showing the device in various positions of extension and indicating in dotted lines the corresponding positions of the pedestals and movable slide members as follows:

Fig. 7 shows the device with the pairs of pedestals moved rearwardly with respect to the table top as the first stage of extension.

Fig. 8 shows the device with the pedestals positioned as in Fig. 7 and with the folding table top extended coplanar with the main table top sections to form a small breakfast or card table suitable for two people.

Fig. 9 shows an extension of the table similar to that shown in Fig. 8 but with the pairs of pedestals moved together longitudinally to provide a small table with a compact central support.

Fig. 10 shows the table with the pedestals separated longitudinally as in Fig. 8 and also sepa-

rated transversely, together with the main table top sections, sufficiently to insert one auxiliary leaf.

Fig. 11 shows the table further extended transversely to receive two auxiliary leaves and with the pairs of pedestals moved together longitudinally.

Fig. 12 is a perspective view of a crossed tie member adapted to connect transverse and longitudinal slide members.

Fig. 13 is a cross sectional view of a number of transverse slide members showing the relation of the slides and stop members adapted to limit the movement of the slides.

The reference characters throughout the several views represent similar parts.

With particular reference to Figs. 1 and 2, 1, 2, 3 and 4 represent the supporting pedestals, of which 1 and 2 at least are equipped with drawers, 5. Near the top of each pedestal is a platform 6 above which is provided space for receiving the system of transverse slides of which the ones indicated at 7 are secured to the platforms of the front pedestals, while those indicated at 8 are attached to the platforms of the rear pedestals. Movable slides 9 interconnect the members 7 and 8 and provide means for relative transverse movement between the front and rear pedestals. Outwardly of the members 7 and in spaced relation thereto the members 10 are secured to the front pedestals and slides 11 are movably engaged between the members 7 and 10. Inwardly of members 8 and in spaced relation thereto the members 12 are secured to the rear pedestals and slides 13 are adapted to move forwardly and rearwardly between members 8 and 12. In right angled relation to the movable slides 11 and rigidly attached thereto are longitudinal slides 14 which are adapted to slide longitudinally between the slide guides 15 and 16 carried by the front section of the table top 17. Similarly attached to the movable slides 13 are longitudinal slides 18 which are movably engaged between the longitudinal guide members 19 and 20 secured to the rear section 21 of the table top.

In order to maintain a rigid right-angled relation between the transverse slides 11 and 13 and their associated longitudinal slides 14 and 18 respectively, I have provided metal braces having crossed transverse and longitudinal arms 22 and 23 respectively which are rigidly secured together at 25 (Fig. 12), preferably by welding.

Dovetailed inserts 26 are utilized as interconnecting means between transverse slide members while rectangular inserts 27 carried by the longitudinal slides move within corresponding ways in the longitudinal slide guides.

Articulated with the rear section 21 of the main table top by suitable flush hinges 28 is a folding top section 29 which is adapted to be folded forwardly on top of the main top sections when the device is used as a desk (Figs. 4 and 5) or extended coplanar with the main table top sections when used as a table (Figs. 1, 2 and 3). Conventional means such as pegs 30 in association with holes 31 (Fig. 2) provide means of maintaining alignment of abutting edges of table top members, including extra table top leaves.

All of the pedestals are provided with wall members 32 which extend above the side panels and provide supports upon which the table top members rest. Also secured to the outer side panels of the rear pedestals are extensions 33 which form supports for the top members associated therewith.

Cross tie members 34 connect the free ends of the slide members 7 and 10 as well as 8 and 12 and provide stop means for limiting the transverse movement of the slides 11 and 13. Stop members 35 (Figs. 2 and 13) secured to the under sides of the slide members 7 and 8 and moving within slots 36 in the intermediate movable slides 9 provide stop means for restricting the movement of the latter by abuttal relation with the ends 37 of the slots 36. The arrangement of these stops and abuttal means is such that when the table is fully extended the stops will prevent further movement of the intermediate slides 9 upon their associated members and so position the slides 9 that the upwardly projecting posts 38 attached thereto will be positioned midway between the inner edges of the main table top members whereby the posts will provide supports for the abutting edges of two auxiliary leaves 39 and 40 (Figs. 2 and 3).

A front or middle drawer 41 is supported by suitable slide means upon the pendant guide members 42 attached to the front section of the table top. When the device is closed to form a desk (Fig. 5) the middle drawer moves rearwardly with the top to occupy a position between the pedestals and upon moving the front top section forwardly the middle drawer is positioned forwardly of the pedestals whereby the latter may be moved longitudinally inward (Fig. 6).

In order to limit the outward longitudinal movement of the pedestals I have provided stop members 43 across the ends of the longitudinal slide guides against which the slides 14 and 18 abut when the pedestals are fully extended longitudinally.

Pendant members 44 carried by the front section of the table and corresponding in vertical dimensions with the rear members 33 provide a means of closing the space above the outer side panels of the front pedestals when the device is closed as a desk (Fig. 4).

If desired, the rear pedestals may be equipped with drawers 45 (Figs. 3 and 4) similar to the drawers 5 in the front pedestals. In this manner the piece may be used as a double desk and its utility extended.

Figs. 7 to 11 inclusively show diagrammatically various positions and stages of expansion adapted to be assumed by my invention in which the pedestals, crossed slides and middle drawer are indicated in dotted lines.

In operation, to convert the device from a closed condition as a desk to a table, the first step is to move the table top sections (still folded) forwardly with relation to the pedestals (Fig. 7). This may be accomplished by pulling the pairs of pedestals rearwardly, one at a time. The pairs of pedestals may then be moved together longitudinally at this stage if desired and the hinged top section extended to form a square breakfast or card table with the pedestals grouped in the center of the table as in Fig. 9, from which position it may be extended transversely by separating the front and rear top sections (together with the front and rear pedestals) to accommodate either one or two extra leaves (Fig. 11). With the two pairs of pedestals moved together as in Figs. 9 and 11 the entire periphery of the table is provided with unobstructed space below the table top for the convenience of persons sitting at the table, whereby four people may comfortably be seated at the small table (Fig. 9) or a large number may be seated at the fully extended table (Fig. 11).

In the event only two people are to use the table the conversion to a small square table is made directly after moving the pedestals rearwardly by simply unfolding the hinged top section as in Fig. 8.

If a larger table than that shown in Fig. 9 is desired but to be occupied by only four persons, the square table of Fig. 9 may merely be extended transversely to accommodate a single extra leaf as in Fig. 10 whereby space is provided between the front and rear pedestals to accommodate persons sitting at the right and left of the table, thus making a conversion suitable for such a group without moving the pedestals longitudinally.

While I have shown a table with an extension sufficient to accommodate two extra leaves, it is to be noted that provision for further extension may be made by introducing additional transverse slides similar to and associated with slides 9.

I claim:

1. A convertible table comprising a main table top having front and rear top sections; a folding top section hinged to the rear of said rear top section and adapted to be folded in superposed relation to said main sections or disposed in coplanar relation therewith; rear longitudinal slide guide means carried by said rear top section; front longitudinal slide guide means carried by said front top section; supporting means for said table top sections comprising two pairs of pedestals, each pair of said pedestals comprising a front and rear pedestal; each pair of pedestals having interconnecting slide means adapting the front and rear pedestals thereof to be optionally disposed in juxtaposed or spaced relation; rear transverse slide guides carried by the rear pedestals of each of said pair of pedestals; rear transverse slides movably supported by said rear transverse guides and adapted to move transversely of the table; front transverse slide guides carried by the front pedestals of each pair of said pedestals; front transverse slides movably supported by said front transverse guides and adapted to move transversely of the table; rear longitudinal slides carried by said rear transverse slides and adapted to move longitudinally of said rear longitudinal slide guide means and front longitudinal slides carried by said front transverse slides and adapted to move longitudinally of said front longitudinal slide guide means.

2. A convertible table comprising a rear top section; a front top section; a folding top section hinged to the rear of said rear top section; two pairs of pedestals for supporting the top sections, each pair of pedestals comprising a front and a rear pedestal; transverse slide means for interconnecting the front and rear pedestals of each of said pairs of pedestals and adapting said front and rear pedestals to be disposed in either juxtaposed or spaced transverse relation; transverse slides movable forwardly and rearwardly with respect to said pedestals and longitudinal slides carried by said transverse slides and movable longitudinally with respect to said top sections.

3. A convertible table having a front main top section; a rear main top section; a folding top section articulated with the rear main top section; supporting means for said top sections comprising four pedestals, said pedestals being arranged in right and left hand pairs of front

and rear pedestals; interconnecting slide means carried by each pair of pedestals for providing relative transverse movement between the front and rear pedestals thereof; rear transverse slide guide means carried by the rear pedestals of each pair; front transverse slide guide means carried by the front pedestals of each pair; rear longitudinal slide guide means carried by the rear main top section; front longitudinal slide guide means carried by the front main top section; right and left rear transverse slides movably supported by said rear transverse guide means; right and left front transverse slides movably supported by said front transverse slide guide means; right and left rear longitudinal slides carried by said right and left rear transverse slides respectively and adapted to move longitudinally within said rear longitudinal slide guide means and right and left front longitudinal slides carried by said right and left front transverse slides respectively and adapted to move longitudinally within said front longitudinal slide guide means.

4. A convertible table comprising a front top section; a rear top section; a folding top section hinged at the rear of said rear top section; four pedestals for supporting said top sections; transverse slide means interconnecting said pedestals with said top sections and adapting the pedestals to be moved transversely of said top sections and longitudinal slide means interconnecting said pedestals with said top sections and adapting the pedestals to be moved longitudinally of said top sections.

5. A convertible table comprising a front top section; a rear top section; a folding top section hinged at the rear of said rear top section and adapted to be disposed coplanar with said other sections or folded in superposed relation thereto; four pedestals for supporting said top sections and slide means interconnecting said top sections with said pedestals and adapting the pedestals to be moved either transversely or longitudinally of said top sections.

6. An extension table comprising a divided table top; two pairs of supporting members; slide means interconnecting the members of each pair of supporting members and adapting the members to be disposed in juxtaposed or spaced transverse relation; transverse slide means interconnecting the supporting members and the top members and adapting the supporting members to be moved transversely of said top members and longitudinal slide means interconnecting the top members and the pairs of supporting members and adapting the pairs of supporting members to be moved longitudinally of said top members.

NORVAL P. SCHREINER.
